UNITED STATES PATENT OFFICE.

FRANK E. HARTER, OF OLYMPIA, WASHINGTON.

SPARK-PLUG.

1,090,815.

Specification of Letters Patent. Patented Mar. 17, 1914.

Application filed July 26, 1912. Serial No. 711,682.

To all whom it may concern:

Be it known that I, FRANK E. HARTER, a citizen of the United States, residing at Olympia, in the county of Thurston, State 5 of Washington, have invented certain new and useful Improvements in Spark-Plugs; and I do hereby declare the following to be a full, clear, and exact description of the invention, such as will enable others skilled 10 in the art to which it appertains to make and use the same.

This invention relates to spark plugs and has for an object to improve this class of devices by the provision of a novel divided 15 electrode adapted to produce a multiple spark gap.

A further object of the invention is to provide a novel insulator for supporting the divided electrode.

With the above objects in view the invention consists of certain novel details of construction and combination of parts herein-after fully described and claimed, it being understood that various modifications may 25 be made in the minor details of construction within the scope of the appended claim.

In the accompanying drawing forming part of this specification:—Figure 1 is a front elevation of the spark plug. Fig. 2 is a longitudinal sectional view through the spark plug. Fig. 3 is a bottom plan view of the spark plug. Fig. 4 is a cross sectional view taken on the line 4—4 Fig. 2. Fig. 5 is a cross sectional view taken on the line 35 5—5 Fig. 2. Fig. 6 is a detail perspective view of one member of the divided electrode.

Referring now to the drawing in which like characters of reference designate similar parts, the spark plug is shown to comprise a central cylindrical core 10 preferably formed of porcelain. The core is provided with an axial opening through which a terminal 11 is engaged. The core is further provided at the lower end with a uniformly enlarged shoulder 12. A metallic externally threaded attaching base 13 bears at the lower end against this shoulder and is provided with a tapered bore which receives the core and into which is threaded a lock 50 nut 14. A wedge ring 15 fits in an annular groove 16 formed in the core, the nipple 17 of the lock nut being tapered to a thin edge

and being interposed between the wedge and base to frictionally lock the core and base together.

The divided terminal consists of a circular series of substantially T-shaped metallic pins 18 the shanks of which are embedded in the bottom face of the porcelain floor, and the heads of which are arcuate in outline and are exposed in their entireties considerably below the bottom face of the core. The shank of one of the pins is extended as shown at 19 and is terminally connected to the metallic attaching base 13. The heads 65 of the pins are spaced slightly apart with resultant spark gaps 20 existing therebetween. The inner terminal 11 is provided with a laterally directed spark point which is directed toward and is slightly spaced 70 from the head of one of the pins as shown at 21. Each time an electric circuit is completed through the terminals 11 and 19, a plurality of sparks will be produced in the spark gaps existing between the separated 75 heads of the pins 18, and the resultant circular series of sparks will positively insure the ignition of the explosive mixture in the engine cylinder.

What is claimed, is:—

In a spark plug, a metallic base, a core of insulating material in said base, a straight central electrode in said core having an exposed straight lower end terminating in a laterally directed spark point, and a second 85 electrode comprising a circular series of T-shaped metallic pins concentrically arranged with respect to the exposed straight lower end of said central electrode and having parallel shanks extending longitudinally 90 in said core and having arcuate exposed heads spaced apart with resultant spark gaps therebetween, the shank of one of said pins being longitudinally prolonged and terminally connected to said base, said spark 95 point extending toward but not contacting with one of said heads.

In testimony whereof, I affix my signature, in presence of two witnesses.

FRANK E. HARTER.
